CLAIM

The ornamental design for a trailer connector as shown and described.

DESCRIPTION

FIG. 1 is a front perspective view of a trailer connector, in accordance with an example implementation of my new design;

FIG. 2 is a rear perspective view of the trailer connector of FIG. 1;

FIG. 3 is a front elevation view of the trailer connector of FIG. 1;

FIG. 4 is a rear elevation view of the trailer connector of FIG. 1;

FIG. 5 is a left side elevation view of the trailer connector of FIG. 1;

FIG. 6 is a right side elevation view of the trailer connector of FIG. 1;

FIG. 7 is a top plan view of the trailer connector of FIG. 1; and,

FIG. 8 is a bottom plan view of the trailer connector of FIG. 1.

The broken lines in the drawings illustrate portions of the trailer connector that form no part of the claimed design.
